184,000

RADIO CABINET FRONT UNIT

Melvin H. Boldt, Glenview, Ill., assignor to Zenith Radio
Corporation, a corporation of Delaware

Application January 24, 1958, Serial No. 49,390

Term of patent 14 years

(Cl. D56—4)

Figure 1 is a front elevational view of a radio cabinet front unit, showing my new design with a radio cabinet and handle being shown in broken lines for illustrative purpose only; and

Figure 2 is a sectional view thereof taken on the line 2—2 of Figure 1 with a fragmentary portion of a radio cabinet being shown in broken lines for illustrative purpose only.

I claim:

The design for a radio cabinet front unit, substantially as shown and described.
